Williamson & Hansen

UNITED STATES PATENT OFFICE.

HANS P. M. HANSEN, OF FREMONT, NEBRASKA.

PROTECTOR FOR THE CORNER-JOINTS OF BEVELED LAP-SIDINGS.

1,366,175.

Specification of Letters Patent. Patented Jan. 18, 1921.

Application filed August 30, 1920. Serial No. 406,750.

To all whom it may concern:

Be it known that I, HANS P. M. HANSEN, a citizen of the United States, residing at Fremont, in the county of Dodge and State of Nebraska, have invented certain new and useful Improvements in Protectors for the Corner-Joints of Beveled Lap-Sidings; and I do hereby declare the following to be a full, clear, and exact description of the invention, such as will enable others skilled in the art to which it appertains to make and use the same.

My invention has for its object to provide a simple and highly efficient protector for the corner joints of beveled lap sidings; and, to that end, generally stated, it consists of the novel devices and combinations of devices hereinafter described and defined in the claims.

As is generally known, it is difficult to make the corner joints of sidings weather tight, without a metal corner protector of some kind. The water will get in and rot the ends of the sidings, especially the overlapping parts. My invention provides an inexpensive corner protector for that purpose, which completely houses said joints and overlaps the sidings below.

My invention is illustrated in the accompanying drawings, wherein like notations refer to like parts throughout the several views.

Referring to the drawings:—

Figure 1 is a perspective of a portion of a corner of an outside wall with lap siding showing my corner protector in working position;

Fig. 2 is a horizontal cross section of the same on the line 2—2 of Fig. 1;

Fig. 3 is a side elevation of my protector detached;

Fig. 4 is a vertical section taken on the line 4—4 of Fig. 3;

Fig. 5 is a bottom plan view of my protector detached; and

Fig. 6 is a plan view of the blank sheet from which my corner protector is made.

The numeral 7 indicates a portion of an ordinary corner post of a wall. The numerals 8 represent the corner portions of the ordinary sheathing and 9 the lap siding.

My protector is secured to the corner of a lower pair of joined sidings by means of two nailing flanges 10, which overlap the lower siding and are secured thereto. A

narrower pair of outer flanges 11 project from said nailing flanges 10, inturned at their bottom, forming seats and a housing for the next upper pair of sidings and the joints thereof. A double vertical partition 13, from which said nailing flanges 10 are bent or folded out, connects said outer flanges with said nailing flanges and cooperates with the same to afford a pair of seats and a housing for the ends of said siding. At the bottom of this partition on both sections, are clenching clips 14 formed by slitting the bottom of the double vertical partition 13 co-incident with each other, adapted to be bent over and buckled against one section of said partition, and so hold said partition together and keep the two sets of flanges in their proper angular relation.

While my invention may be constructed in any suitable way, it is preferably folded out from a single blank sheet of metal of proper form, as shown in Fig. 6. The dotted lines indicate the full lines. The letters *a*, *b*, *c* and *d* designate different folded parts in the respective order in which they are folded. The letter *e* designates projecting ends which are folded to make the inturned bottom of the outer flange and *f* are the clenching clips already described. To form my corner protector, *b* is folded flat on *a* forming the strong double outside flange, and *c* is folded at an angle of 45 degrees toward *b*, making a section of the double partition 13. Then *d* is folded toward *c* in a position parallel with the fold *a*—*b*, making the nailing flange 10. Similarly the other symmetrical sections *a*, *b*, *c* and *d* are folded. Then *a*—*b* is folded toward *a*—*b* at 90 degrees to it, and *c* and *e* are clipped together by bending their flanges *f* and buckling them against *c*. It then remains, to fold *e* over *c* to form the inturned bottom of the flanged housing, as shown in Fig. 5.

In applying my corner protector to the siding, it is nailed onto and overlaps the lower pair of joined siding. Then its pair of upper sidings are put in their seats within the protector, and said sidings are nailed to and slightly overlap the siding below, as shown in Fig. 1. The joints are then completely housed and covered by my protector.

What I claim is:—

1. A protector, for the corner joints of sidings, comprising nailing flanges securable to a lower pair of sidings, and outer

flanges affording seats and a housing for the next upper pair of sidings and the joints thereof.

2. A protector, for the corner joints of sidings, comprising an angular pair of nailings flanges adapted to be secured to and overlap a lower pair of sidings, and angular outer flanges inturned at the bottom affording seats and a housing for the next upper 10 pair of sidings and completely covering the joints thereof.

3. A metallic protector, for the corner joints of sidings, entirely folded out from a single sheet of metal, comprising an angular pair of nailings flanges adapted to be secured to and overlap a lower pair of sidings, angular outer flanges inturned at the bottom affording seats and a housing for the next upper pair of sidings and completely 15 covering the joints thereof, and a double vertical partition connecting the said two sets of flanges and coöperating with the same to make said housing and seats.

4. A protector, for the corner joints of sidings, folded out from a single sheet of metal, comprising an angular pair of nailings flanges of one thickness of said metal, adapted to be secured to and overlap a lower pair of sidings, angular outer flanges of double 20 thickness of the metal inturned at the bottom

affording seats and a housing for the next upper pair of sidings and the joints thereof, and a double vertical partition connecting the said two sets of flanges and coöperating with the same to make said housing and 35 seats.

5. A protector, for the corner joints of sidings, folded out from a single sheet of metal, comprising an angular pair of nailings flanges of one thickness of said metal, adapted to be secured to and overlap a lower pair of sidings, angular outer flanges of double thickness of the metal inturned at the bottom affording seats and a housing for the next upper pair of sidings and the joints 40 thereof, a double vertical partition connecting the said two sets of flanges and coöperating with the same to make said housing and seats, and a clenching clip on the bottom of both sections of said partition serving to 45 hold the same together and keep the two said sets of flanges in their proper angular relations.

In testimony whereof I affix my signature in presence of two witnesses.

HANS P. M. HANSEN.
